AGITATOR MECHANISM FOR WASHING MACHINES

Robert J. Waterworth, Sidney, Ohio

Application October 8, 1936, Serial No. 104,722

20 Claims. (Cl. 259—99)

This invention relates to washing machines and pertains particularly to improvements in the agitator mechanism thereof.

In washing machines of the types at present in use, the agitators therein, or the means by which the clothes in the tub are thrown back and forth, produce a washing action on the clothes only around the wall of the tub and no washing action at the center of the tub is had. There 10 is thus formed what might be termed a zero point in the washing effect of the agitator upon the clothes.

The present invention has for its primary object to provide an improved agitator operating 15 means whereby a definite washing action of the clothes will be had at the center of the tub in addition to the customary outside and near-center action which is now obtained with the conventional washer.

Another object of the invention is to provide 20 an improved agitator operating mechanism by which the clothes in the tub will be caused to pass back and forth from one side of the tub to the other across the center of the tub in a path which substantially describes a figure eight so that in addition to the water action upon the 25 clothes there is obtained a massaging or scrubbing action upon the same as they pass over the agitator and as they reverse their motion at the sides of the tub.

A still further object of the invention is to provide in a washing machine an improved agitator operating mechanism therefor whereby the agitator will be caused to perform a combined horizontal and oscillatory movement and a reciprocatory movement in the tub.

A still further object of the invention is to provide agitator operating mechanism therefor whereby there is obtained a constant reciprocatory movement and an oscillatory movement 40 in a horizontal plane having constantly varying extent of movement transversely of the tub.

The invention will be best understood from a consideration of the following detailed description taken in connection with the accompanying drawings forming part of this specification, with the understanding, however, that the invention is not confined to any strict conformity with the showing of the drawings but may be changed 45 or modified so long as such changes or modifications mark no material departure from the salient features of the invention as expressed in the appended claims.

In the drawings:

Figure 1 is a view in vertical section through an agitator and the operating mechanism therefor constructed in accordance with the present invention, the agitator mechanism being shown in operative position relative to the bottom of a tub.

Fig. 2 is a horizontal section on the line 2—2 of Fig. 1.

Fig. 3 is a horizontal section on the line 3—3 of Fig. 1.

Fig. 4 is a vertical section taken on the line 4—4 of Fig. 3.

Fig. 5 is a graph illustrating the paths followed by the ends of the agitator fins and the points at the center of the device where the fins cross.

Fig. 6 is a sectional view on the line 6—6 of Fig. 2.

Fig. 7 is a diagrammatic view illustrating a modified arrangement of the gears and connecting means between the same and the agitator unit whereby the constantly varying horizontal oscillatory motion of the unit is obtained.

Figs. 8 and 9 illustrate two of the positions assumed by the agitator operating mechanism during the course of operation of the same by the modified arrangement described in connection with Fig. 7.

Fig. 10 illustrates diagrammatically the motions of the tips of a four-blade agitator when operated by gears of unequal tooth ratio.

Referring now more particularly to the drawings, the numeral 1 designates the vertically sectioned portion of the center part of the bottom of the tub upon which the agitator mechanism is mounted. The central part of the tub bottom is provided with an opening 2 and overlying this opening and disposed at the underside of the tub bottom is a casting comprising a circular plate 3 which is separated from the tub bottom by a gasket 4, and which has formed integrally therewith the upwardly extending sleeves 5 which project through the opening 2 into the interior of the tub. A reinforcing annulus 6 is placed upon the inner surface of the tub in concentric relation with the plate 3 and suitable securing elements such as rivets 7 are passed through the annulus 6 and the plate 3 to maintain the parts in assembled relation. These rivets or securing elements also function to maintain in position against the underside of the plate 3 a gear casting 8 to which reference will be made herein- 45 after.

The underside of the plate 3 is provided with a recessed boss 9 for the reception of an end of a drive shaft 10 and adjacent this boss the plate has formed therein the aperture 11 in which is secured one end of a stub shaft 12.

The housing 8 is formed to receive in its bottom or horizontal wall the other end of the stub shaft 12, as illustrated in Fig. 4, and is also provided with a bearing opening 13 through which the shaft 10 extends to the outside of the housing to receive a belt pulley 14 or any other suitable means for establishing a driving connection between the mechanism and motor.

Within the housing 8 the shaft 10 carries a 60

gear pinion 15 which meshes with the larger gear 16 which rides freely upon the stub shaft 12. Integral with the gear 16 is a pinion 17. This pinion meshes with an overlying gear 18 which in turn meshes with the gear 19 which is disposed in a common plane therewith.

The gears 18 and 19 are secured respectively to the vertical shafts 20 and 21 which pass upwardly through the sleeves 5 through the packing material 22, as illustrated in Fig. 1. By means of the material 22 and the packing nuts 23, the shafts 20 and 21 pass out of the upper ends of the sleeves 5 into the interior of the tub and water is prevented from flowing from the tub down 15 through the sleeves and leaking out.

At their upper ends the shafts 20 and 21 carry the crank arms 24 and 25, the same being secured to the vertical shafts in any suitable manner, as by the cross pins 26.

20 The numeral 27 designates a link by which the cranks 24 and 25 are coupled and this link as shown is provided with the longitudinally extending slot 28 and at one end with a pin receiving aperture 29. The aperture 28 receives a crank 25 pin 30 which is carried by and extends upwardly from the free end of the crank arm 26, and this pin, as shown in detail in Fig. 6, has an encircling groove 31 formed about its upper end to receive the inner end of the retaining pin 32 which is 30 threaded through the side of the link 27. By this means the pin 30 is held securely by the crank arm 26 but is permitted to rotate in the aperture 28 in the link. The slot or guide-way 28 in the link has mounted therein a slide block 34. In this block there is pivotally engaged the upper end of a crank pin 33 which is carried at the free end of the crank arm 24.

The agitator is indicated generally by the numeral 35, and this comprises a circular plate 36 in the central part of which is formed the downwardly opening box or housing 37. Extending over and across this housing 37 which is of elongated rectangular formation, as shown in Fig. 2, are the vertically disposed right angularly related 45 fins 38.

The link 27 is provided with suitably threaded apertures to receive securing screws 39 which are passed through the top of the housing 37 and which firmly secure the link in the housing and 50 against the underside of the top thereof, as shown in Fig. 1.

In the illustration of the invention as set forth in Figs. 1 to 4 inclusive, the gears 18 and 19 are of the same number of teeth, and in assembling 55 the parts the cranks are first disposed substantially in the relation illustrated in Fig. 2. In this relation the cranks when being rotated will not pass over the center line at the same time. When power is applied thru the drive shaft 10, 60 the gears 18 and 19 will be simultaneously rotated in opposite directions and while the pivot pin 30 for the crank 35 will remain fixed with relation to the link 27, the pin 33 will move longitudinally of the link with the block 34 in slot 28. This 65 will impart to the agitator unit 35 a combined horizontal oscillatory motion in the tub and a reciprocatory motion. In other words, the motion of the agitator is always a cycle of angular movement across the center of the tub and repeat 70 and, where an agitator is employed which has four fins as shown, the tips of those fins or blades which are parallel with the link 27 describe a substantially quarter-moon outline as indicated by the numeral 40 in Fig. 5, and the center of the 75 blades where they join describe elliptical paths,

as indicated at 41. The tips of the other two blades describe the distorted figure 8 outlines, indicated by the numeral 40' and the centers where these other two blades or fins cross also describe similar figure 8 outlines as indicated at 41'.

It is also contemplated within the scope of the present invention to effect a variation in the oscillatory reciprocatory movement of the agitator by substitution of gears of unequal tooth ratio for the gears 18 and 19.

In Figs. 7, 8 and 9, there are illustrated diagrammatically several positions which the connecting link 27 between the cranks will assume in the actuation of the agitator by coupling in the place of gears 18 and 19, gears of unequal tooth ratio. In substituting a gear having one more or one less tooth than its mate, it will also be necessary to substitute crank arms of shorter length so that the same can pass without having their ends meet. Referring particularly to Fig. 7, let the outline indicated by the numeral 18' represent a gear of thirty teeth and the outline 19' represent a gear of 32 teeth. The cranks 24' and 25' correspond to the cranks 24 and 25 previously described but are shorter so that their ends may pass, as illustrated in this figure. The link is indicated by the numeral 27'. In starting the gears will be assembled so that the long ends of the cranks will be in opposed relation as shown and the agitator and link are placed in position so that the link will be parallel with the aligned cranks. It will be apparent from this that when the gears 18' and 19' start to rotate, the first movement of the link will be a circular reciprocatory movement, but since the gear 18' has less teeth than the gear 19' it will rotate slightly faster than the larger gear so that the free or outer end of the link 27 will gradually swing in an arc of constantly increasing extent transversely of the tub as it performs a reciprocatory movement. When the smaller gear has rotated relative to the larger gear to the point where the crank pin associated therewith will have advanced a quarter revolution when the pin of the larger gear is in starting position, the link 27' will assume the position shown in Fig. 8 so that its upper end will be describing a very wide arc transversely of the tub, and when the pin of the smaller gear has advanced three-quarters of the way ahead of the pin of the larger gear, the link will assume the position shown in Fig. 9. It will be understood that from the starting position of Fig. 7 through the two positions shown in Figs. 8 and 9, and back to the starting position, the free end of the link will have gradually increased the extent of its arcuate movement to a maximum point and then come back to the position where it started, as shown in Fig. 7.

While I have referred particularly to a gear tooth ratio of 30-32, it will be understood that any desired unequal ratio may be employed so that the rapidity of the agitation may be increased or decreased as desired.

The class of agitation produced by the unequal ratio of gears is from a transverse oscillatory motion to the angular across-center motion as a peak, and then back down to the transverse oscillatory, after which the cycle will be repeated, and if, for instance, the gears 18 and 19 have forty-two and forty-three teeth respectively, the cycle of change is forty-two revolutions.

In the structure illustrated in Figs. 1 to 4, where an equal number of teeth are shown upon the gears 18 and 19, it has been found by actual test

that this gives water action across the tub similar to a rocking tub. The dashing action across the tub carries the clothes in a wide vertical figure 8 or a double elliptic path up over one side of the agitator and down past the other. This is with reference to a full tub of clothing. The same action occurs when a few pieces of clothing are in the tub but there is an intermittent floating about and turning over of the clothes. With a tub full of clothes this agitation changes the relative positions of the garments, passing them one over the other, and they not only get the effect of being rubbed against one another and the outer sides of the tub, but they are rubbed by the agitator blades and the bottom of the tub as they flow in the figure 8 path described.

In the diagram constituting Fig. 10 there are illustrated the four circular areas 42, 42', 43 and 43', which represent the motion of each of the four tips of the blades 38 when starting to operate the agitator with gears of unequal tooth ratio, assuming that the same is started with the parts related as illustrated in Fig. 7. If tracer points were placed at the tips of each of the four blades, there would be obtained figures as shown in this diagram, therefore the complete blade or fin which parallels the link 27' moves transversely of the tub between the lines 44 and the other blade will move between the lines 45. The blades have an endwise movement equal to twice the radius of one throw of the cranks 24', 25'. After considering the movement for one revolution or a part thereof there begins a change of figure or pattern until the tips of the blades reach a peak in their movement, of quarter-moons and distorted figure 8's similar to the diagram forming Fig. 5, whereupon they will then return to the figure outlined in Fig. 10.

40 I claim:

1. In a washing machine including a receptacle having a bottom, an agitator unit therein permanently disposed in close proximity to the bottom, a pair of rotary driven supporting members for the agitator, and pivotal connecting means between said members and said unit having positive relative movement simultaneously with rotary movement imparted by the driven members and moving the agitator constantly in a plane paralleling said bottom.

2. In a washing machine including a receptacle having a bottom, an agitator unit therein permanently disposed in close proximity to the bottom, a pair of elements between the unit and said bottom and mounted for rotation in a common plane paralleling said bottom, means for rotating said elements, and coupling means between the elements and the agitator so constructed and arranged that upon rotation of the elements the agitator will be given simultaneously an oscillatory and a reciprocatory movement.

3. In a washing machine including a receptacle, an agitator unit therein, a pair of elements mounted for rotation in a common plane, means for driving said elements, and coupling means between the elements and the agitator constructed and arranged to give to the agitator a reciprocatory movement and a simultaneous oscillatory motion the extent of which is constantly and progressively varied from a minimum to a maximum.

4. In a washing machine including a receptacle, an agitator unit therein, a pair of elements mounted for rotation in a common plane, means for simultaneously oppositely rotating said ele-

ments, a pivotal coupling between one element and the agitator and permanently located relative to the agitator, and a pivotal coupling between the other element and the agitator which is slidable to move relative to the agitator during its rotation.

5. In a washing machine including a receptacle, an agitator unit therein and maintaining a permanent spaced relation with the bottom of the receptacle, a pair of crank elements mounted for rotation in a common plane which parallels the bottom of the receptacle, driving means rotating the elements in opposite directions, and a pivotal coupling means between the elements and the agitator, the said elements with which the agitator is connected being between the agitator and receptacle bottom.

6. In a washing machine including a receptacle, an agitator unit therein and maintaining a permanent spaced relation with the bottom of the receptacle, a pair of crank elements mounted for rotation in a common plane which parallels the bottom of the receptacle, driving means rotating the elements in opposite directions, a pivotal coupling means between the elements and the agitator, the said elements with which the agitator is connected being between the agitator and receptacle bottom, and one only of said couplings also being slidable.

7. In a washing machine including a receptacle, an agitator unit therein, a pair of crank elements, the agitator having a part lying over the elements, driving means rotating the cranks in opposite directions, means forming a pivotal connection between the agitator and one crank, means providing a guide slot which is movable with the agitator, and means carried by the other crank element having sliding and pivotal engagement in said slot.

8. In a washing machine, including a receptacle having a bottom, an agitator unit therein in relatively close permanently spaced relation with said bottom, a pair of cranks arranged for rotation in a common plane which parallels said bottom and having a part of the agitator lying thereover, means for imparting rotation to the cranks in opposite directions and at the same speed, a pivotal connection between the cranks and the overlying part of the agitator, and means whereby one of said connections is reciprocated in the plane of rotation.

9. In a washing machine including a receptacle, an agitator unit therein, a pair of cranks arranged for rotation in the same plane and having a part of the agitator lying thereover, means for imparting rotation to the cranks in opposite directions, means imparting a differential speed of rotation to the cranks, a pivotal connection between the cranks and the overlying part of the agitator, and one of said connections being adapted for reciprocation in the plane of rotation.

10. In a mechanism of the character described, including a receptacle having a flat bottom, an agitator in the receptacle and lying in close proximity to said bottom, a pair of vertical shafts, means for rotating the shafts in opposite directions, a crank upon the upper end of each shaft, the cranks being positioned to rotate in a common plane parallel with said bottom, a pin carried by each crank, said agitator having a portion formed to provide a downwardly opening casing for housing the cranks, means pivotally coupling one pin with a top wall of the agitator casing permitting relative movement of the same in a

horizontal plane, and pivotal coupling means between the other pin and the said top wall of said casing which is fixed against such relative movement.

5 11. In a mechanism of the character described, including a receptacle having a flat bottom, an agitator in the receptacle lying in close proximity to said bottom, a pair of vertical shafts, means for rotating the shafts in opposite directions, a 10 crank upon the upper end of each shaft, the cranks being positioned to rotate in a common plane parallel with said receptacle bottom, a pin carried by each crank, said agitator having a downwardly opening casing for housing the 15 cranks, means forming a sliding pivotal connection between a wall of the casing and one of said pins, said sliding connection being in a plane parallel with the plane of rotation of the cranks, and a pivotal connection between the other pin 20 and said wall of the casing which is fixed relative to the agitator.

12. In a washing machine including a receptacle, an agitator unit disposed within and adjacent the bottom of the same, a pair of elements 25 mounted for rotation in a common plane which parallels said bottom, means for driving said elements, and coupling means between the elements and the agitator so constructed and arranged as to give an oscillatory motion to opposite extreme 30 parts of the agitator in a plane paralleling said receptacle bottom and a simultaneous reciprocation of the same in said plane.

13. A mechanism of the character described, comprising a pair of directly coupled gears, 35 means for imparting rotary motion directly to one gear, the other gear being driven by the said one gear, a crank carried by each gear, an agitator, and coupling means between the agitator and said cranks, one of said couplings being slidable 40 relative to the agitator.

14. In a washing machine, an agitator, a receptacle within the lower part of which the agitator is permanently housed, mechanism supported by and at the underside of the receptacle 45 for transmitting power movement to the underside of the agitator within the receptacle; and means coupling said mechanism with the agitator for causing the agitator to maintain a constant reciprocatory movement over the bottom of 50 the receptacle and to simultaneously oscillate on an axis perpendicular to said bottom.

15. In a washing machine, an agitator, a receptacle within the lower part of which the agitator is permanently housed, a pair of relative- 55 ly movable members coupled with the agitator and so constructed and arranged as to effect oscillatory motion of the agitator in constantly repeated cycles each of which comprises a plurality of oscillations progressively increasing from a 60 minimum to a maximum degree of movement and simultaneous reciprocation of the same, and means for delivering driving motion to said members.

16. A mechanism of the character described, 65 comprising a pair of toothed gears having toothed connection, means for imparting rotary motion directly to one gear, the other gear being driven by the said one gear whereby the gears have opposite rotation, a crank carried by each gear, an 70 agitator, and coupling means between the agitator and said cranks, one of said couplings being

slidable relative to the agitator, and said gears being of unequal tooth ratio.

17. In a washing machine having a fixed receptacle having a flat bottom, a pair of short shafts extending vertically in parallel relation thru said bottom, a wheel upon each shaft, said wheels being coupled directly one with the other for opposite rotation, means for imparting rotary movement to one wheel, a crank upon each shaft within the receptacle and in a plane common to one another and parallel with the bottom, an agitator lying in the receptacle in close proximity to said bottom and covering said shafts and cranks, a pivotal connection between both cranks and the agitator, and means whereby one of the said pivotal connections has sliding movement relative to the agitator.

18. In a washing machine having a fixed receptacle having a flat bottom, a pair of short vertical shafts extending vertically in parallel relation through said bottom, a wheel upon each shaft, said wheels being coupled directly one with the other for opposite rotation, means for imparting rotary movement to one wheel, a crank upon each shaft within the receptacle and in a plane common to one another and parallel with the bottom, an agitator lying in the receptacle in close proximity to said bottom and covering said shafts and cranks, a pivotal connection between both cranks and the agitator, means whereby one of the said pivotal connections has sliding movement relative to the agitator, and said wheels being of unequal circumferential ratio whereby the rotation of one will be of greater speed than the other.

19. In a washing machine having a fixed receptacle having a flat bottom, a pair of short vertical shafts extending vertically in parallel relation through said bottom, a wheel upon each shaft, said wheels being coupled directly one with the other for opposite rotation, means for imparting rotary movement to one wheel, a crank upon each shaft within the receptacle and in a plane common to one another and parallel with the bottom, an agitator lying in the receptacle in close proximity to said bottom and covering said shafts and cranks, a pivotal connection between one crank and the agitator, there being an elongated slot at the underside of the agitator at one end of which said pivotal connection is located, and an element carried by the other crank and disposed in said slot to have oscillatory movement and reciprocatory movement therein.

20. In a washing machine having a receptacle with a flat bottom, an agitator in the receptacle having a hollow body portion opening toward the said bottom and upstanding integral blades, the said body being in closely spaced relation with said bottom, a gear mechanism housed beneath said bottom and under said body to receive power from a power source, and mechanism housed in the hollow body and coupled through said bottom with the gear mechanism which is so constructed and arranged that said body and blades will have imparted thereto upon actuation of the gear mechanism a reciprocatory motion in a plane paralleling said bottom and simultaneously an oscillatory motion about an axis perpendicular to said bottom.
